US0D1015041S

(12) **United States Design Patent** (10) **Patent No.:** **US D1,015,041 S**
(45) **Date of Patent:** **** Feb. 20, 2024**

(54) **KETTLE**

(71) Applicant: **Hebei Fenger Intelligent Technology Co., Ltd.**, Shijiazhuang (CN)

(72) Inventors: **Jianzhong Zhang**, Handan (CN); **Zuo Yang**, Handan (CN)

(73) Assignee: **Hebei Fenger Intelligent Technology Co., Ltd.**, Shijiazhuang (CN)

(**) Term: **15 Years**

(21) Appl. No.: **29/827,208**

(22) Filed: **Feb. 18, 2022**

(51) LOC (14) Cl. **09-01**

(52) U.S. Cl.
